[57] CLAIM

The ornamental design for a lavatory, as shown and described.

DESCRIPTION

FIG. 1 is a perspective view taken from the top, front and left side of a lavatory embodying our new design; FIG. 2 is a top plan view thereof;

FIG. 3 is a front elevational view thereof;

FIG. 4 is a right side elevational view thereof, the left side being the mirror image of the right side;

FIG. 5 is a rear elevational view thereof;

FIG. 6 is a cross-sectional view taken on line 6—6 of FIG. 2;

FIG. 7 is a cross-sectional view taken on line 7—7 of FIG. 2; and,

FIG. 8 is a bottom plan view of the embodiment of FIG. 1.

The fragmentary broken line representations of mounting holes in FIGS. 1 and 2 are for the purpose of illustration only and form no part of the claimed design.
